PROCESS AND APPARATUS FOR THE UTILIZATION OF ARTIFICIAL THREAD

Arthur L. Snyder, Garden City, N. Y., assignor, by mesne assignments, to E. I. du Pont de Nemours & Company, Wilmington, Del., a corporation of Delaware

Application April 3, 1936, Serial No. 72,621

16 Claims. (Cl. 66—125)

This invention relates to improvements in knitting apparatus and method of knitting, more particularly it relates to a modified form of knitting apparatus suitable for use in the knitting of fabrics directly from spun cakes of artificial thread.

By the term "spun cakes" is meant artificial thread cakes which are formed in centrifugal thread collecting buckets when the artificial thread is passed thereinto from the coagulating and/or regenerating bath. Spun cakes of artificial thread, after being formed in the centrifugal spinning buckets, are subjected to washing, desulfuring and bleaching solutions and then dried before they can be used for the production of textiles. These various operations result in entanglement of the individual threads and windings of spun cakes.

Heretofore, it has therefore been considered necessary to rewind artificial thread from the spun cake into cones before the said thread can be satisfactorily knitted into fabric.

It has now been found, however, that fabrics may be knitted directly from spun cakes of artificial thread which have previously been subjected to the various washing, purifying and finishing operations by proper modification of previously known knitting processes and apparatus.

It is therefore an object of this invention to provide a method for the treating of spun cakes and knitting fabrics directly therefrom.

It is another object of this invention to provide an improved form of knitting apparatus suitable for use in the knitting of fabrics directly from spun cakes.

It is a further object of this invention to provide a knitting apparatus with auxiliary devices which will permit the same to be used for the knitting of fabrics directly from spun cakes.

Other objects of the invention will be apparent by reference to the following detailed description taken in connection with the accompanying drawings illustrating one specific embodiment of the invention, and, in which:

Figure 1 is a diagrammatic front elevation, with parts shown in sections, of a knitting apparatus constructed in accordance with the invention.

Figure 2 is a top plan view of a pair of cooperating furnishing wheels.

Figure 3 is a front elevational view of the wheels shown in Figure 2.

Figure 4 is a perspective view of a spun cake supporting means.

Figure 5 is a front elevational view of a knitting machine tension head.

Figure 6 is a side elevational view of the tension head shown in Figure 5.

Figure 7 is a vertical sectional view of a spun cake in position on a supporting means, having a thread draw-off guiding means positioned thereon.

Figure 8 is a perspective view of a thread draw-off guiding means.

The spun cakes of artificial thread after purifying and washing in a known manner are centrifuged to remove most of the liquid therefrom and subjected to treatment with a finishing and lubricating liquid. The spun cakes are then dried and humidified in a known manner and directly mounted on the thread supports of a knitting machine. The finishing and lubricating liquid is preferably applied to the spun cakes by subjecting the latter to a shower with water containing from 3 to 20 grams per liter of a suitable finishing, flexibilizing and lubricating composition. Any finishing and flexibilizing composition which will soften the thread and impart thereto the desired hand and appearance is suitable for this purpose. The cakes are preferably subjected to such a shower for a period of from two to six hours at a temperature of about 50° C. After treating the cakes with the finishing and lubricating liquid they are dried and humidified in accordance with standard practice, after which they will be satisfactory for the knitting operation.

Heretofore, knitting machines such as, for example, the Wildman Spring Needle Body Machine, manufactured and sold by the Wildman Manufacturing Co. of Norristown, Pa., were commonly provided with a thread tension regulating and automatic stop means, such as, a tension head or furnishing wheel mechanism to be described hereinafter.

The thread tension regulating and automatic stop means serves to deliver yarn to the knitting needles at a uniform tension and/or to stop the knitting operation when the tension on the thread is excessive.

Referring now to the drawings, reference numeral 15 designates generally the supporting frame work of a knitting machine. Numeral 17 designates the knitting cylinder of the machine, in which are positioned the conventional arrangement of guides, needles and cams for carrying out the actual knitting operation. The various threads 19 are passed to the guides 21 of the 55

knitting cylinder from stationary guides 23 positioned near to the furnishing wheel mechanism.

The furnishing wheel mechanism comprises a plurality of pairs of positively rotated conical gear wheels 25. The gear wheels 25 are positioned on substantially parallel stubshafts 27 thereby to cause said gear wheels to be in full mesh with each other at one end and only partially enmeshed at the other end. The gear 10 wheels are preferably geared to a drive shaft 26 so as to be rotated at a constant uniform speed. The threads 19 are passed between sets of gear wheels 25 which function to draw or furnish the thread to the knitting cylinder. The thread may 15 be moved in a direction parallel to the axes of the wheels and between the same, thereby causing the thread to be furnished to the cylinder at varying speeds and to compensate for variations in tension between the thread package and the 20 furnishing wheels. Positioned directly under each set of gear wheels 25 is a pivoted thread guide 29 which is connected to a conventional stop motion mechanism. When the thread 19 breaks the thread guide 29 drops and thereby 25 actuates the mechanism, such as is well known in the art, to stop the knitting machine. A freely rotatable weighted disc 31 is positioned directly over each set of gear wheels 25. A weight 33 is adjustably connected to each disc 31. Each 30 disc 31 also has thread guides 35 and 37 securely fixed thereto. A stationary thread guide 39 is preferably positioned directly over each disc 31. The thread guides 35 and 37 which are fastened to rotatable disc 31 are adapted to move the 35 thread in an axial direction between the furnishing gear wheels in a manner to be described hereinafter.

When knitting directly from spun cakes there 40 will be numerous jerks or changes in thread tension due to catching of the individual thread windings which are somewhat entangled with each other. Due to this jerky thread delivery difficulty has been encountered from frequent machine stoppages caused by the dropping of thread 45 guides 29 when the thread tension is suddenly released. When the knitting machinery is caused to stop by action of the guides 29 and the presser cams of the knitting machinery a "mis-press" is caused in the knitted fabric. A mis-press in a 50 fabric is considered a defect and is therefore very objectionable. In order to eliminate mis-presses in the fabric it was found necessary to remove the conventional presser cam rods from the knitting machinery. Upon removal of the presser 55 cam rods it was found that the knitting machinery could not be stopped quickly enough in case of thread breakage. The free thread end was therefore knitted into the fabric and large 60 holes or "quarters" resulted from the fabric being pressed off the needles.

In order to correct this condition the furnishing wheels were raised above the knitting needles a considerable distance, e. g. at least 18 inches 65 and preferably 24 inches. The knitting machine when modified in this manner will not cause mis-presses, and will eliminate the knitting of free threads into the fabric.

The threads 19 are preferably led from the 70 thread cakes 41 over thread draw-off guiding means 43, through thread compressors 45, through cooperating tension equalizers 47 and 49, over tension head 51, and thence through stationary guides 39 hereinabove referred to.

75 Each thread draw-off guiding means 43 com-

prises a core 53 and a disc 55. The disc 55 is provided with a highly polished, curved flange 57 (see Figures 7 and 8). The thread draw-off guiding means functions to guide the thread 19 as it is being drawn from the thread cake 41. 5 The particular form of this guiding means may obviously be modified in many ways without departing from the nature and spirit of the invention.

Each yarn compressor 45 comprises a small, 10 hard cylindrical guide member, composed of porcelain, hard rubber, artificial resin or similar substance. The yarn compressor 45 is preferably positioned directly over the center of the spun cakes 41 and contains a thread opening of very small 15 diameter, e. g. about 60 drill gauge. The yarn compressor functions to prevent the passage therethrough of more than one thread when a plurality of loops or windings are simultaneously 20 pulled up from the cakes 41, and consequently any modified form of device which will function in this capacity will serve as a yarn compressor.

The tension equalizer 47 comprises a spring suspended rod having a thread guide positioned on the end thereof. The spring 46 will permit the free movement of equalizer 47 in any direction. The cooperating tension equalizer 49 comprises a rod 61, a pivotal bar 63, a pivot pin 65 and a weighted rod 67. The weight 69 on said weighted rod 67 is preferably adjustably connected thereto. The cooperating tension equalizers 47 and 49 function to prevent sharp or sudden changes in tension in the thread when the thread is not immediately loosened from the spun cake. When knitting directly from spun cakes 35 the thread must often be pulled from a tucked under position and from ridges and crinkles in the cake formation. The pulling of the thread under such conditions causes sudden sharp 40 changes in the tension on the thread and thereby breaks the latter or pulls the same from the trigger of the tension head. The tension equalizers are therefore preferably constructed with comparatively long arms which may cooperate to give a considerable length of slack thread which 45 may be taken up under a very gradual increase in tension and thereby loosen the thread before a high tension is imparted thereto. The specific construction of the tension equalizers is merely 50 illustrative and any device of similar nature which will provide a considerable length of slack thread upon gradual increase in tension will be suitable as a thread tension equalizer.

The tension head 51, which functions as a 55 thread tension releasing means, comprises a supporting rod 71, a supporting collar 74, a plate 73, a trigger 75 and a stop motion actuating rod 81. The trigger 75 is pivoted at 71 and is held in a substantially horizontal position by means of a spring which is adjustable for any desired 60 tension. A rod 81 is also connected to the trigger 75. The several rods 81 from the tension head are in turn connected to a stop motion mechanism by means of rods 83 in a known manner. The thread is looped over the trigger 75. When the tension on the thread exceeds the tension of the spring holding the trigger in the horizontal position, the trigger will be moved downwardly and the thread will slide from the trigger, 70 thereby causing a stopping of the knitting machine.

Inasmuch as the tension heads serve somewhat the same function as the furnishing wheel mechanism, the former has been used only in the ab- 75

sence of a furnishing wheel mechanism. It has now been found, however, that when the tension head mechanism is used in combination with a furnishing wheel mechanism a result may be accomplished which is impossible to achieve with either device when used alone. In the direct knitting of fabric from spun cakes it was found that the jerky yarn delivery caused a frequent thread breakage when furnishing wheels alone were used. On the other hand when only a tension head was used the thread was continuously cast from the trigger of the tension head, thereby causing very frequent stopping of the knitting machine. However, when the tension head was used in combination with furnishing wheels substantially continuous operation without excess thread breakage was capable of achievement despite frequent variations in the tension of the thread.

It has furthermore been found that certain sharp increases in thread tension can be avoided to a large extent by means of an improved cake supporting means. It was found that a cake supporting means having a plurality of resilient prongs 91 which are fastened to a base 93 with inwardly off-set portions 95 adjacent base 93 very materially prevented catching of the loosely wound threads between the bottom of the support and the spun cakes. Excess thread tensions and thread breakage caused by so-called "tuck unders" were therefore materially reduced. The prongs 91 are provided at their tops with inwardly projecting portions to form a cradle for the core 53 of the thread draw-off guiding means.

The improved knitting apparatus functions substantially as follows:

The threads 19 pass from the spun cakes 41 through the yarn compressors 45, through the tension equalizers 47 and 49 which will prevent any sudden increase in thread tension by taking up the slack between them as they move toward each other. From the tension equalizers the threads pass over the triggers of the tension head through stationary thread guides 39, through rotatable thread guides 35, between the conical furnishing gear wheels, then through the pivoted thread guides 29 and rotatable thread guides 37. When the tension on one of the threads increases as it passes from guide 29 to guide 23, the guide 37 will be pulled downwardly thereby, rotating the weighted disc 31 in a clockwise direction. As disc 31 is rotated the guide 35 will be rotated in a clock-wise direction thereby moving the thread between the furnishing gear wheels to a point where said gear wheels are in a deeper meshed position with each other, and consequently cause the thread 19 to be fed to the knitting cylinder at a higher speed thereby decreasing the tension between the furnishing rolls and the knitting needles.

Fabric knitted directly from spun cakes in the manner and with the apparatus hereinabove described was found to be at least of equal quality and in some cases of substantially superior quality than similar fabrics knitted from precision wound cones. The stitch was found to be uniform with no trace of abnormal formation of stitch or pin holes, and the shade and luster of the fabric was more pleasing.

Probably the most important comparison in the cloth knitted from cakes against cloth knitted from cones is that of strip-backs. "Strip-backs" are caused by broken filaments in the yarn strip-

is light in denier, and terminating in a slub. This is a very troublesome defect for those knitters making quality cloth. Obviously if the spun cakes are first wound into a precision wound cone, the thread cleaning mechanism, the wash-board tension mechanism, and the various guides on the winding machines will aggravate this defect whenever broken filaments occur in the spinning operation. The guides on the knitting machines do not affect the broken filaments to the same extent because there is less abrasive action on the threads.

During the comparative test of cloth knitted from spun cakes in accordance with the present invention and the knitting of cloth from precision wound cones, a comparison was made from 31 rolls of cloth knitted from spun cakes against 19 rolls of cloth knitted from cones on the same machines and at the same machine adjustment. A detailed inspection report of these rolls was summarized as follows:

	Average of strip-backs per pound	Average of slubs per pound	25
Cloth knitted from cakes.....	0.137	0.189	30
Cloth knitted from cones.....	0.493	0.192	35

It will be obvious that many changes and modifications of the process and apparatus above described may be made without departing from the nature and spirit of the invention. It is therefore to be understood that the invention is not to be limited except as set forth in the appended claims.

I claim:

1. In a knitting apparatus suitable for use in knitting fabrics directly from spun cakes of artificial thread, cake supporting means, said cake supporting means having off-set portions to prevent pressure on said cakes at the lower internal periphery thereof, positively driven thread feeding mechanism for feeding the thread to knitting needles; thread tension releasing means, thread compressor means, and thread tension equalizing means, said releasing means, compressor means and equalizing means being positioned between said cake supporting means and said thread feeding mechanism.

2. In a knitting apparatus suitable for use in knitting fabrics directly from spun cakes of artificial thread, cake supporting means, said cake supporting means having off-set portions to prevent pressure on said cakes at the lower internal periphery thereof, positively driven thread feeding mechanism for feeding the thread to knitting needles; thread tension releasing means, and thread tension equalizing means positioned between said cake supporting means and said thread feeding mechanism.

3. In a knitting apparatus suitable for use in knitting fabrics directly from spun cakes of artificial thread, cake supporting means, said cake supporting means having off-set portions to prevent pressure on said cakes at the lower internal periphery thereof, positively driven thread feeding mechanism for feeding the thread to knitting needles; thread tension releasing means, and thread tension equalizing means positioned between said cake supporting means and said thread feeding mechanism, said thread feeding mechanism being positioned at least 18" from any knitting needles.

4. In a knitting apparatus suitable for use in

75

- knitting fabrics directly from spun cakes of artificial thread, a cake supporting means, positively driven thread feeding mechanism for feeding the thread to knitting needles; thread tension releasing means and thread tension equalizing means positioned between said cake supporting means and said thread feeding mechanism.
5. In a knitting apparatus suitable for use in knitting fabrics directly from spun cakes of artificial thread, a cake supporting means, positively driven thread feeding mechanism for feeding the thread to knitting needles; thread compressor means, thread tension releasing means, and thread tension equalizing means, said compressor means, releasing means and equalizing means being positioned between said cake supporting means and said thread feeding mechanism.
6. In a knitting apparatus suitable for use in knitting fabrics directly from spun cakes of artificial thread, a cake supporting means, said cake supporting means having off-set portions to prevent pressure on said cakes at the lower internal periphery thereof, positively driven thread feeding mechanism for feeding the thread to knitting needles, and thread tension releasing means positioned between said cake supporting means and said thread feeding mechanism.
7. In a knitting apparatus suitable for use in knitting fabrics directly from spun cakes of artificial thread, a cake supporting means, positively driven thread feeding mechanism for feeding the thread to knitting needles, and thread tension releasing means positioned between said cake supporting means and said thread feeding mechanism.
8. In a knitting apparatus suitable for use in knitting fabrics directly from spun cakes of artificial thread, a cake supporting means, positively driven thread feeding mechanism for feeding the thread to knitting needles, and thread tension releasing means and thread compressor means positioned between said cake supporting means and said thread feeding mechanism.
9. In a knitting apparatus suitable for use in knitting fabrics directly from spun cakes of artificial thread, cake supporting means, said cake supporting means having off-set portions to prevent pressure on said cakes at the lower internal periphery thereof, positively driven thread feeding mechanism for feeding the thread to knitting needles, and thread tension equalizing means positioned between said cake supporting means and said thread feeding mechanism.
10. In a knitting apparatus suitable for use in knitting fabrics directly from spun cakes of artificial thread, a cake supporting means, positively driven thread feeding mechanism for feeding the thread to knitting needles, and thread tension equalizing means positioned between said cake supporting means and said thread feeding mechanism.
11. In a knitting apparatus suitable for use in knitting fabrics directly from spun cakes of artificial thread, a cake supporting means, positively driven thread feeding mechanism for feeding the thread to knitting needles, and thread compressor means and thread tension equalizing means positioned between said cake supporting means and said thread feeding mechanism.
12. In knitting fabrics directly from spun cakes of artificial thread, cake supporting means, said cake supporting means having off-set portions to prevent pressure on said cakes at the lower internal periphery thereof, a plurality of knitting needles, thread tension releasing means and thread tension equalizing means positioned between said cake supporting means and said needles.
13. In a knitting apparatus suitable for use in knitting fabrics directly from spun cakes of artificial thread, a cake supporting means, a plurality of knitting needles, and a thread compressor means positioned between said supporting means and said needles, said compressor means comprising a cylindrical guide member having a thread opening sufficiently small to prevent the passage therethrough of more than one thread.
14. In a knitting apparatus suitable for use in knitting fabrics directly from spun cakes of artificial thread, a cake supporting means, positively driven thread feeding mechanism for feeding the thread to knitting needles, and thread tension equalizing means positioned between said cake supporting means and said thread feeding mechanism, said equalizing means comprising a plurality of cooperating, yieldable thread guides adapted to provide slack thread upon gradual increase in thread tension.
15. In a knitting apparatus suitable for use in knitting fabrics directly from spun cakes of artificial thread, a cake supporting means, positively driven thread feeding mechanism for feeding the thread to knitting needles, and thread tension equalizing means positioned between said cake supporting means and said thread feeding mechanism, said equalizing means comprising a plurality of cooperating thread guides mutually yieldable toward each other by increased tension applied to the thread.
16. In a method, for knitting fabrics from spun cakes of artificial thread, the steps comprising subjecting said cakes to treatment for 2 to 6 hours with a shower of a finishing liquid containing 0.3% to 2.0% of a suitable finishing composition in water, supporting said cakes on a knitting machine, feeding said thread from said cakes to knitting needles, and substantially eliminating sharp changes in thread tension and thread breakage due to variations in pull necessary to remove the thread from said cakes.

ARTHUR L. SNYDER.
